UNITED STATES PATENT OFFICE.

GEORGE P. ALTENBERG, OF CINCINNATI, OHIO, ASSIGNOR TO THE ICY-HOT BOTTLE COMPANY, OF CINCINNATI, OHIO, A CORPORATION OF WEST VIRGINIA.

DESIGN FOR A VACUUM-INSULATED JUG AND CASING THEREFOR.

57,567.

Specification for Design.

Patented Apr. 26, 1921.

Application filed September 8, 1919. Serial No. 322,587. Term of patent 14 years.

To all whom it may concern:

Be it known that I, GEORGE P. ALTENBERG, a citizen of the United States, residing at Cincinnati, in the county of Hamilton and State of Ohio, have invented a new, original, and ornamental Design for a Vacuum-Insulated Jug and Casing Therefor, of which the following is a specification, reference being had to the accompanying drawing, forming part thereof.

My new, original and ornamental design for a vacuum insulated jug and casing therefor is shown in the accompanying drawing, in which—

The figure is a perspective view of a vac-

uum insulated jug and casing therefor, showing my new design.

I claim:

The ornamental design for a vacuum insulated jug and casing therefor, substantially as shown.

GEORGE P. ALTENBERG.
